UNITED STATES PATENT OFFICE.

WILFRED BARNES, OF FOREST PARK, ILLINOIS, ASSIGNOR TO EDISON ELECTRIC APPLIANCE COMPANY, INC., OF CHICAGO, ILLINOIS, A CORPORATION OF NEW YORK.

DESIGN FOR A COMBINED ELECTRIC-HEATER CASING AND STANDARD.

Application filed December 26, 1922. Serial No. 4,706. Term of patent 14 years.

To all whom it may concern:

Be it known that I, WILFRED BARNES, a citizen of the United States, residing at Forest Park, in the county of Cook, State of Illinois, have invented a new, original, and ornamental Design for a Combined Electric-Heater Casing and Standard, of which the following is a specification, reference being had to the accompanying drawing, forming a part thereof.

The accompanying drawing shows a per-

spective view of a combined electric heater casing and standard embodying my new design.

I claim:—

The ornamental design for a combined electric heater casing and standard substantially as shown.

In witness whereof, I have hereunto set my hand this 11 day of December, 1922.

WILFRED BARNES.
